SILL CONSTRUCTION

William Mearns, Jr., Maplewood, N. J.

Application August 25, 1932, Serial No. 630,369

6 Claims. (Cl. 20—64)

This invention relates to elevator door sill constructions, the same being peculiarly adapted for use in office buildings, hotels and institutions and has for its principal objects the provision of an attractive, compact and inexpensive construction which is adapted to render it possible to leave the temporary wood or other coverings on the finished frames or jambs undisturbed pending the completion of the building, while permitting 10 of the laying, finishing and cleaning of the floors without damaging such finished frames or jambs. Other advantages of the invention are herein-after set forth.

Heretofore in various buildings having elevator shafts, it has been customary to provide a slab-like sill across each elevator doorway and to extend the door-frame or jambs down to sill or floor level. In office buildings, hotels and the like, wherein numerous elevators are installed, it 15 is customary to leave the greater portion of the temporary wood or other coverings with which the finished metal jambs have been protected by the manufacturer to prevent marring of the same during shipment and erection, to remain on the jambs during the erection of the building, but in order to permit of the laying and finishing of the floors, it has been necessary to remove such temporary wood or other covering from the bottom 20 portions of such jambs. Such removal of the bottom portion of the temporary covering exposed the bottom of the jambs with the result that during the laying and finishing of the floor, whether the same was of terrazza or other cement bonded material, the bottom portions of the 25 jambs frequently were marred and rendered unsightly either because of the action of the rubbing machine or of the action of the cement which was used to bond the rubble or floor particles together as a result of the same having become splashed 30 thereon. Furthermore, in the periodic cleaning of these floors, even after the building was finished and the entire temporary coverings on the jambs had been removed, there was a tendency for the cleaning machine or the mops or the 35 cleaning materials used to mar or otherwise injure the finish on the bottom of the jambs. Since these jambs were frequently finished with a baked enamel coating, the same became permanently defaced as a result of such marring either during 40 the original laying or finishing of the floor or during the subsequent cleaning thereof.

My investigations have led to the discovery of a form of construction of elevator door sill which, as above stated, is not only attractive in appearance and economical to construct, but is also free

from the aforesaid objections and furthermore, such construction renders it possible to leave undisturbed the temporary wood or other coverings on the frames or jambs, as applied thereto by the manufacturer until the entire building is completed without in any way interfering with the laying and finishing of the floors.

My invention is fully set forth and described in the detail description and drawing forming a part thereof in which latter

Figure 1 is a fragmentary front elevation of an elevator shaft equipped with my improved sill construction;

Fig. 2 is a horizontal section on the line 2—2 of Fig. 1;

Fig. 3 is a vertical section on the line 3—3 of Fig. 2 and

Fig. 4 is a cross-section on the line 4—4 of Fig. 3.

Referring to the drawing and the construction shown therein, the reference numeral 1 designates the elevator shaft of a building, 2 the corridor walls of a building, 3, 3' the opposing jambs or side frames of the elevator door openings, 4, 4' the side trim, 5, 5' the elevator doors and 6 the corridor floor. My improved door sill proper comprises a unitary structure preferably of metal, consisting of opposing terminal uprights or plinths 10, 10' which serve to support said jambs and an integral interconnecting web or sill element 11, the same having slots 12, 12' to receive the tongues 13, 13' on the bottom of the respective elevator doors. Said sill has a depending marginal flange 14 which projects over the rear edge of the floor. As shown, the bottom of the inner faces of the plinth elements, and the portion of the sill adjacent the same are curved and merge into each other so as to eliminate any sharp angle at the junction there-between and thereby facilitate the maintenance of the same in a clean sanitary condition.

Preferably my improved unitary sill and plinth member is cast from a single piece of metal such as cast iron, bronze, aluminum alloy or the like.

While in many cases it is preferable that the entire portion of each plinth and the entire sill member be cast as an integral unit, nevertheless, it may be desirable where the only objects to be accomplished are the protection of the jambs during the erection of the building and the subsequent cleaning of the floors thereof, or the reduction in the expense for patterns is desirable, that the upper portion of the plinths be formed as separate units and be screwed or bolted to abbreviated plinths cast on each end of the

sill proper or even that separate plinth members be provided which are mortised or otherwise secured to the opposing ends of the sill proper, as distinguished from being cast integral therewith, and it is therefore intended that such constructions be embraced within the scope of certain of the appended claims.

As shown, in my preferred construction of elevator door sill, the sill is formed of a single piece of metal throughout its entire width. It is evident, however, that the portion of the sill carrying the door grooves may be a separate flat sill which is splined or keyed to the main sill that carries the integral plinths at its opposite ends, though in such construction it would obviously be highly desirable to fill up the longitudinal crevice or joint between the two sill members with solder or the like in order to eliminate any possibility for the tendency of debris to collect therein.

As is apparent from the foregoing, my improved elevator door sill construction is unusually sturdy and durable and such construction admits of the floors and sill being scrubbed or mopped during the periodic cleaning of the building corridors without risk of damaging the ornamental jambs or frames and, furthermore, in my preferred form of construction no debris can collect, since the plinths are integral with the sill and consequently there are no joints, such as is now the case in all present constructions between the base of the jambs and the sill.

By the term "solid pedestals" as used in the claims, is intended to refer to a solid base or support upon which the jamb is adapted to rest as distinguished from a socket adapted to receive such jamb.

Various changes within the scope of the appended claims may be made without departing from the spirit of my invention as embraced therein.

Having thus described my invention, what I claim and desire to obtain by United States Letters Patent is:

1. An elevator door sill, comprising a sill member having opposing terminal plinths, constituting solid pedestals, and adapted to support a

door jamb at a level corresponding to the top of such pedestal formed integral therewith.

2. An elevator door sill, comprising a sill member having opposing terminal plinths, constituting solid pedestals, and adapted to support a door jamb at a level corresponding to the top of such pedestal formed integral therewith, the bottom of the inner surfaces of the respective plinths and the adjacent portion of the sill being curvilinear and gradually merging into each other.

3. An elevator door sill, comprising a casting having a sill member and opposing plinth members, constituting solid pedestals, and adapted to support a door jamb at a level corresponding to the top of such pedestal formed integral therewith, said sill member being grooved to receive the elevator door guides.

4. In a building construction, the combination comprising a corridor, flooring on said corridor, an elevator shaft adjacent the corridor, said shaft having door openings at the different levels of the building, elevator doors for closing said openings, elevator door sill members spanning the bottom of the door openings, each of said sill members having opposing terminal plinth members, constituting solid pedestals, a door jamb supported on each plinth member in such a manner that the extreme bottom of the door jamb is on the level with the top of said plinth member and a marginal flange projecting over the edge of the corridor flooring which is adjacent the shaft.

5. An elevator door sill, comprising a sill member, opposing terminal plinths, constituting solid pedestals, and adapted to support a door jamb at a level corresponding to the top of such pedestal rigidly secured thereto and serving as supports for the door jambs, whereby the latter are maintained in spaced relation with respect to the door sill level and an adjacent floor.

6. An elevator door sill, comprising a sill member proper and opposing plinth members, constituting solid pedestals, and adapted to support a door jamb at a level corresponding to the top of such pedestal connected thereto, at least a portion of each plinth being formed integral with at least a portion of the sill.
